DESIGN FOR A SPOON.

SPECIFICATION forming part of Design No. 22,196, dated February 7, 1893.

Application filed November 10, 1892. Serial No. 461,562. Term of patent 3½ years.

To all whom it may concern:

Be it known that I, JUSTUS VERSCHUUR, a citizen of the United States, residing at Jersey City, in the county of Hudson and State of New Jersey, have invented and produced a new and original Design for Spoons; and I do hereby declare the following to be a full, clear, and exact description of the invention, such as will enable others skilled in the art to o which it appertains to make and use the same, reference being had to the accompanying drawing, and to letters of reference marked thereon, which form a part of this specification.

5 The figure of the drawing is deemed sufficient to fully illustrate the design, the said figure representing the obverse side of a spoon.

The leading features of the design consist in a spoon, the handle of which is decorated o with a representation of Santa Claus, and the bowl with a picture of a Christmas tree.

In said drawing, A indicates the broader part of the handle of a spoon, B is the narrower part or shank and C the bowl of the

spoon. The bowl is decorated on the concave 25 side thereof with a picture or representation of a Christmas tree, d, having a star e, at its upper extremity. The shank is decorated with representations of holly leaves and berries, f, and with a bird, g, singing in the midst 30 of the same. At the wide extremity of the handle, the same is decorated with a representation of "Santa Claus," h, holding a toy in one hand and with the other stroking his beard. 35

What I claim is

The design for a spoon herein described consisting of a spoon decorated on the handle with the figure of "Santa Claus" and on the bowl with the figure of a Christmas tree, substantially as shown and described. 40

In testimony that I claim the foregoing I have hereunto set my hand this 1st day of November, 1892.

JUSTUS VERSCHUUR.
